P. GRABLER

COPYHOLDER APPARATUS

Filed Oct. 17, 1924

UNITED STATES PATENT OFFICE.

PETER GRABLER, OF ROCKY RIVER, OHIO.

COPYHOLDER APPARATUS.

Application filed October 17, 1924. Serial No. 744,176.

To all whom it may concern:

Be it known that I, PETER GRABLER, a citizen of the United States, residing in Rocky River, county of Cuyahoga, and State of Ohio, have invented a new and useful Improvement in Copyholder Apparatus, of which the following is a specification.

My invention relates to apparatus for holding one or more copies.

10 One object of my invention is a simple, inexpensive, neat, easily operable, and efficient copy holder apparatus.

Another object is to provide such an apparatus with means for holding one or more 15 copies.

Another object is to provide such an apparatus with means for tilting either one or both of the copy holder means to adjust the same angularly or inclinedly to suit the convenience of the operator.

Another object is to provide such an apparatus with a sight space to enable the operator to follow the text of the copy without loss of time and without inconvenience.

25 Another object is to provide such an apparatus with means for selectively moving the copy in relation to the sight space and with means for indexing this copy.

Another object is to provide such an apparatus with means for permitting the copy moving means to be operated without affecting the copy indexing means.

Another object is to provide such an apparatus with means for indexably or digitally moving and indexing one of the copy holder means and to extend the operating end of this means to within easy reach of the operator.

Another object is to provide such an apparatus with means for adjusting the indexing means to different line spacing on a copy.

Another object is to provide such an apparatus with means for manually and selectively moving or operating the copy moving means without interfering with the copy indexing means.

One embodiment of my invention is illustrated in the accompanying drawing in which,

Fig. 1 is a front view of a copy holder apparatus embodying the features of my invention and showing two copy holder means, also means for indexably or digitally and for selectively moving one of the copy holder means, and also the sight space. 50

Fig. 2 is a section, taken on a vertical plane indicated by the line 2—2 in Fig. 1, showing the spacer shaft in relation to the base and to the plate. 55

Fig. 3 is a section, taken on a vertical plane indicated by the line 3—3 in Fig. 7, showing the index operating means longitudinally. 60

Fig. 4 is a section, taken on a vertical plane indicated by the line 4 in Fig. 8, showing the roller and the shaft thereof in relation to the casing of the copy moving means on the top of the plate. 65

Fig. 5 is a section, taken on a vertical plane indicated by the line 5—5 in Fig. 1, 70 showing the transverse relation between the members of the copy moving means and the relation thereof to the plate and the adjusting strip between the upper end of the plate and the copy moving means. 75

Fig. 6 is a sectional view showing means for holding the auxiliary copy holder.

Fig. 7 is a section, taken on a vertical plane indicated by the line 7—7 in Fig. 1, showing the index operating means transversely. 80

Fig. 8 is a side view of Fig. 1.

Similar reference characters refer to similar parts throughout the views.

All of the sectional views are drawn to a larger scale. 85

The apparatus shown in the accompanying drawing comprises, principally, the base A, the copy support plate B, the copy moving means C, the copy indexing means D, and the auxiliary copy holder E. 90

The upwardly extending ears 10 are provided on the base A and have an opening therethrough for the purpose appearing presently. The forwardly extending arm 11 is provided on the base A and has the adjusting screw 12 threaded therein and also has the spring 13 resting in a counter- 95

bore therein, and also has the pad 14 resting in a counterbore therein, and also has the ears 15 through which the pivot screw 16 passes; the purpose of the members 12, 13, 5 14, and 16 will appear presently.

The bottom of the base A is provided with the feet 17 of rubber or other cushioning or nonabrasive material.

The plate B is formed of sheet metal with 10 the side edges bent down to form the longitudinal flanges 18 to stiffen the plate longitudinally and to provide a means for supporting other members of the apparatus as will appear presently. The top edge of 15 the plate B is also bent down to form the transverse flange 19 to stiffen the plate transversely and to provide a base to support the copy moving means C.

The adjusting strip 20 is interposed between 20 the top of the plate B and the bottom of the copy moving means C.

The copy moving means C has the frame 21 resting on the adjusting strip 20 and also has an upwardly extending ear 22 at each 25 end thereof. The frame 21 is secured to the flange 19 by the screws 23 which also pass through the strip 20. The copy roller shaft 24 is journaled in the ears 22 and extends a short distance beyond these ears 30 and is provided with the knob 25 on each end thereof.

The plates 26 are secured to the outside of each end of the frame 21 and extend forward of the frame.

35 The square shaft 27 extends between the plates 26 and has the round ends 28 journaled in the forward end of the plates 26.

The lower portion of each of the brackets 29 encompasses the square shaft 27 and the 40 upper portion thereof supports the lower sight bar 30 which extends substantially the full length of the frame between the ears 22.

The lower portion of each of the brackets 31 encompasses the square shaft 27 and the 45 upper portion thereof is formed as a journal for the pin 32 to which the roller 33 is secured. The lower square portion of each bracket 31 is first made a little smaller than the shaft 27 and is, preferably, provided with inherent spring tendency to frictionally grip this shaft so that these brackets 31 with the rollers 33 journaled therein can be moved along the shaft 27 to any desired longitudinal position to accommodate different widths of copy and to remain in this adjusted position without manipulating any releasing or locking means.

60 The eye bolts 34 are secured to the shaft 27 near the end of the square portion thereof.

The rollers 35, two in the present instance with the space 36 between them, are secured to the shaft 24 and extend between 65 the ears 22.

The tension springs 37 have one end thereof secured to the eye bolts 34 and the other end thereof to the ears 22. The object of these springs is to normally tend to rotate the shaft 27 to hold the rollers 33 70 against the rollers 35 and thereby hold the copy against the rollers 35.

The handles H are secured to the shaft 27 and serve the purpose of manually rotating the same to remove the rollers 33 75 from the rollers 35 when it is desired to release the copy or for other purposes.

The upper sight bar K has the ends bent down to form the ears 38 which are hinged to the ears 22 by the hinge screw 39. 80

It is observed that the upper sight bar as well as the lower sight bar are hinged to the frame 21. This arrangement permits either one or both bars to be moved or swiveled and thereby increase or decrease 85 the width of the sight space 40, or to swivel the upper sight bar out of the way, or for other purposes.

The sprocket 41 is secured to the roller shaft 24 and occupies the space 36 between 90 the rollers 35.

A lug 42 is secured to the lower end of the flanges 18 of the plate B by the screws 43 and these lugs are disposed inside of the ears 10 and in alignment and in contact therewith.

A hinge joint is formed between the bottom of the plate B and the ears of the base A, on each side of the plate B, to permit 100 the plate B to be swiveled on the base A for the purpose of angular adjustment of the plate B to suit the convenience of the operator.

Each of these hinge joints (Fig. 3) comprises the sleeve 44 passing through the ear 10 and through the lug 42 and one end thereof is provided with the head 45 bearing against the lug 42. The nut 46 is threaded to the other end of the sleeve 44 and bears against the ear 10.

By means of these nuts 46, the hinge joints can be adjusted so that sufficient friction exists between the members thereof to permit the plate B to be swiveled on the base A to adjust the copy to the convenience of the operator and to retain the plate B in any adjusted position without manipulating the adjustment of these hinge joints.

This swivel joint arrangement permits the operator to adjust the copy to desired position and the friction feature of these joints permits of such adjustment and at the same time holds the plate B in whatever position it has been adjusted to. This swivel joint feature also permits the plate B to be swiveled way down to substantially parallel position with the arm 11 so that the apparatus as a whole may be folded up into compact form for shipment or storage.

The spacer shaft 47 is journaled in the

sleeves 44 and has the collar 48 pinned to one end thereof to prevent longitudinal movement of the shaft in one direction.

The drive cup 49 is secured to the other end of the shaft 47 by the pin 50 passing through the hub 51 and through the shaft 47. The end of the hub 51 bears against the sleeve 44 to prevent longitudinal movement of the shaft 47 in the other direction.

10 The cover 52 is journaled on the other end of the shaft 47, adjacent to the cup 49 and is held in position by the nut 53 threaded to the end of the shaft 47.

15 The bracket 54, secured to the base A, has the neck 55 extending upward through the space 56 provided for that purpose between the open end of the cup 49 and the cover 52. The upper end of the neck 55 has the projection 57 extending into the cup 49 for the 20 purpose appearing presently.

The lever 58 is fulcrumed on the base A between the ears 15 by the pivot screw 16. The rear end of the lever 58 carries the pivot screw 59 which is threaded into the 25 cover 52 and which has the pilot 60 extending into the cavity of the cup 49. The purpose of this pilot is to confine the roller 61 between the block 62 and the inner wall 63 of the cup 49 as seen in Fig. 7, so that the 30 roller can not fall out of place when the apparatus is held in different positions.

The block 62 is riveted to the cover 52 in an inclined position so that the side 64 thereof forms a wedge face in relation to the 35 wall 63.

The roller 61 lays loosely against the wall 63 and against the projection 57 and does not contact the side 64 when the index mechanism is in normal position as seen in Fig. 7.

40 When the index mechanism is in this position, a rotative movement of the cup 49, in either direction, permits the roller 61 to rotate on the wall 63 without contacting the side 64 of the block 62 since the cover 52 is 45 rotatable on the shaft 47 and is now held against rotation by the lever 58, thereby retaining the roller 61 loosely in the cup 49.

When the front end 65 of the lever 58 is 50 pressed down, the rear end 66 moves upward as shown by the arrow in Fig. 7. Since this end 66 is secured to the cover 52 by the screw 59, this upward movement of this end 66 rotates the cover 52 in the direction of the arrow shown thereon. Since the 55 block 62 is secured to the cover 52 it rotates therewith.

When the block 62 so moves with the cover 52, the clearance 67 is first taken up and the roller 61 is then wedged in between the side 64 of the block 62 and the wall 63 of the cup 49 whereby the cup 49 is locked to the cover 52 and must rotate therewith. The shaft 47 must rotate with the cup 49 since they are secured to each other by the pin 50.

60 Upon release of the front end 65 of the

lever 58, the spring 13 returns the rear end 66 to original position. In such return movement, the roller is not gripped between the side 64 and the wall 63 and can freely move down, due to gravity, until it abuts the projection 57 as seen in Fig. 7. The end 66 of the lever then moves a little further downward and thereby rotates the cover 52 and the block 62 thereon a little further to provide the clearance 67.

75 The pad 14, preferably of rubber or other similar material, limits the downward movement of the rear end 66 of the lever.

The adjusting screw 12 is provided to limit the upward movement of the rear end 66 of the lever. Upon manipulation of the screw 12, the travel of the end 66 of the lever, and consequently of the cover 52, can be adjusted to suit different spacing on the 80 copy.

The sprocket 68 is secured to the spacer shaft 47 and the sprocket 41 is secured to the roller shaft 24 in alignment with the sprocket 68. The chain 70 connects both of these 85 sprockets.

90 When a copy is placed into this apparatus, between the rollers 35 and 33, it may be adjusted in the sight space 40 by rotating the roller 35 by means of the knobs 25. This rotation of the rollers 35 also rotates the sprocket 41 which, in turn, rotates the shaft 47 and the cup 49 thereon through the chain 70 and the sprocket 68.

95 As previously stated, the cup 49 can rotate in either direction without affecting the index mechanism, therefore, the adjustment of the copy in relation to the sight space can be carried out without affecting the index mechanism.

100 After the copy is so adjusted, the adjusting screw 12 is manipulated so that the index mechanism rotates the rollers 35 in conformity to the line spacing on the copy when the end 65 of the lever is pressed down until it contacts the adjusting screw 12.

105 After the index mechanism is so adjusted, each manipulation of the lever 58 moves the copy according to the adjustment while the copy can be adjusted independently by means of the knobs 25 without affecting the 110 index mechanism.

115 The auxiliary copy holder means E is hinged to the plate B and extends forward thereof.

120 The brackets 71 have the lower portions thereof secured to the respective flanges 18 by the screws 72 and the upper ends thereof are formed with the journal portions 73 for the bar 74.

125 Each of these journal portions has the flange 75 and the screw 76 passing through this flange and is threaded to the portion adjacent to this flange. This arrangement permits the journal to be adjusted by means of the screw 76 so that there is just suffi- 130

cient friction between the bar 74 and the portion 73 to permit the bar 74 to be rotated in the journal 73 but to remain in any position it has been rotated or adjusted to.

5 The bar 74 has the end portions adapted to the journals 73 as stated, and also has the side portions 77 extending forward of the plate A, and also has the longitudinal front portion 78. The journal at 73 permits 10 the portion 78 to be moved up and down in front of the plate B.

The bracket 79 has the lower portion 80 formed to encompass the portion 78 of the bar 74 and is provided with sufficient inherent spring tendency to frictionally engage this portion 78 to permit the bracket 79 to be rotated thereon and to remain in whatever position it has been rotated to.

15 The auxiliary copy holder 81 is supported 20 on the bracket 79 and has the clips 82 to hold the same thereon.

This arrangement of the auxiliary copy holder means permits the copy holder 81 to be put on or taken off of the bracket at 25 will, and also permits this copy holder to be adjusted up and down by means of the swivably journaled bar 74, and also permits this copy holder to be adjusted angularly to suit the convenience of 30 the operator, and also permits this copy holder to be removed from the apparatus and further permits the bar 74 as well as the bracket 79 to be folded close to the front of the plate B for the purpose of shipment, or storage, or to have this mechanism out of the way when only one copy is to be supported on the apparatus.

35 When it is desired to adjust the chain 70, the adjusting strip 20 is replaced by 40 one thinner or thicker as required.

I am aware that modifications may be made within the scope of the appended claims; therefore, without limiting myself to the precise construction and arrangement 45 of elements shown and described, I claim:—

1. An apparatus of the character described comprising, a plate for supporting a copy, a roller shaft journaled at one end of said plate, rollers secured to said roller shaft to move the copy, a space between certain of 50 said rollers, and means for rotating said roller shaft confined within said space between the rollers and back of said plate.

2. An apparatus of the character described comprising, a plate for supporting a copy, roller means at one end of said plate for suspending and moving the copy, means for rotating said roller means by means of a movable member of the apparatus, said 55 means for rotating the roller means confined within the boundaries of said roller means and back of said plate, and means for manually rotating said roller means independent of the first mentioned means for rotating 60 the roller means.

3. An apparatus of the character described comprising, a plate for supporting a copy, a spacer shaft journaled at one end of said plate, means for indexably rotating said spacer shaft, roller means at the other end of said plate for suspending and moving the copy, means operated by said spacer shaft for rotating said roller means, said means for rotating the roller means confined back of said plate, that end of said 75 means for rotating the roller means which engages said roller means confined within the boundaries of said roller means, and means for manually rotating said roller means independent of the first mentioned 80 means for rotating the roller means.

4. An apparatus of the character described comprising, a plate for supporting a copy, roller means at one end of said plate for moving the copy, sight bars extending 85 longitudinally of said roller means and spaced to form a longitudinal sight space between them, and at least one of said sight bars adjustable to adjust the width of said sight space.

5. An apparatus of the character described comprising, a base, a spacer shaft journaled in said base, means for rotating said spacer shaft, a plate having the lower end thereof hinged to said base concentric with said spacer shaft, a roller shaft journaled on the upper end of said plate, means for manually rotating said roller shaft, and means operatively connecting both of said shafts for rotating the same 95 100 in unison when either of said shafts is rotated.

6. An apparatus of the character described comprising, a base, a spacer shaft journaled in said base, means for rotating said spacer shaft, a plate having the lower end thereof hinged to said base concentric with said spacer shaft, a bracket bolted to the upper end of said plate, a roller shaft journaled in said bracket, means for manually rotating said roller shaft, a sprocket secured to said spacer shaft, a sprocket secured to said roller shaft in alignment with said sprocket on the spacer shaft, a chain engaging both of said sprockets to rotate both of said shafts in unison, and a removable strip between said plate and said bracket to adjust the tension of said chain.

7. An apparatus of the character described comprising, a base, a spacer shaft journaled in said base, a plate having the lower end thereof hinged to said base concentric with said spacer shaft, a roller shaft journaled on the upper end of said plate, two rollers secured to said roller shaft with a space between them and thereby expose a portion of said roller shaft, and means confined within said space and engaging said exposed portion of the roller shaft for rotating both of said shafts in unison.

8. An apparatus of the character described comprising, a base provided with a forwardly extending arm, a spacer shaft journaled in said base, means on one end of said shaft for indexably rotating said spacer shaft, a lever fulcrumed on said forwardly extending arm and substantially parallel therewith and extending forward thereof for operating said means for indexably rotating the spacer shaft, and a plate having one end thereof hinged to said base and adapted to swivel forward to substantially parallel and adjacent position with said arm and with said lever to permit the apparatus to be folded into compact form for shipping or storage. 65
9. An apparatus of the character described comprising, a base provided with a forwardly extending arm, a copy support plate extending upward from said base, a rotatable copy roller means on the upper end of said plate to move the copy longitudinally of said plate, a spacer shaft journaled in said base, means on said spacer shaft for rotating the same, a lever pivoted on said arm and parallel therewith and extending forward thereof and adapted to partly rotate said spacer shaft upon manual operation of this lever, and means for positively transmitting the exact rotative movement of said spacer shaft to said copy roller means. 70
10. An apparatus of the character described comprising, a base provided with a forwardly extending arm, a plate extending upward from said base, a rotatable copy roller means on the upper end of said plate, a spacer shaft journaled in said base, means on said spacer shaft for rotating the same, a lever pivoted on said arm and provided with means for engaging and disengaging said means for rotating the spacer shaft, resilient means for normally holding said means on the lever in disengaging position, an adjusting screw in the path of said lever to adjust the pivotal movement thereof and thereby adjust the rotative movement of said spacer shaft, and means for transmitting the rotative movement of said spacer shaft to said copy roller means. 75
11. An apparatus of the character described comprising, a base, a plate extending upward from said base, a rotatable copy roller means on the upper end of said plate, a spacer shaft journaled in said base, a drive cup secured to said spacer shaft, a cover journaled on said spacer shaft adjacent to the open end of said cup, a dog secured to said cover and extending into said cup, a roller loosely confined between said dog and the inner circumferential wall of said cup, a stop extending into said cup to limit the travel of said roller in one direction, means for partly rotating said cover whereby said dog locks said roller to said inner wall to partly rotate said spacer shaft, and means for transmitting said rotative movement of said spacer shaft to said roller means. 80
12. An apparatus of the character described comprising, a base provided with a forwardly extending arm, a copy support plate extending upward from said base, a rotatable copy roller means on said plate, a spacer shaft journaled in said base, drive means secured to said spacer shaft, a cover journaled on said spacer shaft and provided with means for rotatively engaging said drive means, said engaging means normally free to permit said spacer shaft to rotate in either direction, a lever fulcrumed on said arm and having one end thereof operatively connected to said cover to rotate the same and thereby rotate said drive means and said spacer shaft upon manipulation thereof, means associated with said lever for adjusting the movement of said one end thereof to limit the rotative movement of said spacer shaft to suit different spacing between the lines of the copy, and means for transmitting said rotative movement of said spacer shaft to said copy roller means. 85
13. An apparatus of the character described comprising, a base provided with a forwardly extending arm, a copy support plate extending upward from said base, a rotatable copy roller means on said plate, a spacer shaft journaled in said base, drive means secured to said spacer shaft, a cover journaled on said spacer shaft and provided with means for rotatively engaging said drive means in one direction, said engaging means normally free to permit said spacer shaft to rotate in either direction, a lever fulcrumed on said arm and having one end thereof operatively connected with said cover to rotate the same in said one direction only and thereby rotates said drive means and said spacer shaft in the same direction upon manipulation of this lever, spring means for returning said lever to original position, means associated with said lever for adjusting the movement of said one end thereof to limit the rotative movement of said spacer shaft, and means for transmitting the rotative movement of said spacer shaft to said roller means. 90
14. An apparatus of the character described, comprising, a base, a copy support plate extending upward from said base, a copy roller means on said plate, a spacer shaft journaled in said base, drive means for said spacer shaft normally permitting the same to rotate in either direction and adapted to automatically engage and rotate the same in one direction only upon manipulation of this drive means, means for operating said drive means to partly rotate said 120
15. An apparatus of the character described, comprising, a base, a copy support plate extending upward from said base, a copy roller means on said plate, a spacer shaft journaled in said base, drive means for said spacer shaft normally permitting the same to rotate in either direction and adapted to automatically engage and rotate the same in one direction only upon manipulation of this drive means, means for operating said drive means to partly rotate said 125

spacer shaft, and chain and sprocket means for transmitting the rotative movement of said spacer shaft to said copy roller means.

15. An apparatus of the character described comprising, a copy support plate, roller means on the upper end of said plate for supporting a copy and adapted to be manually rotated in either direction, a spacer shaft journaled on the lower end of said plate and normally free to rotate in either direction, means for periodically rotating said shaft in one direction only, and means operatively connecting said roller means and said shaft whereby said manual rotation of the roller means transmits a similar rotative movement to said spacer shaft and said rotative movement of the shaft transmits a similar rotative movement to said roller means.

20. 16. An apparatus of the character described comprising, a copy support plate, a roller means journaled on one end of said plate for suspending a copy and adapted to be manually rotated in either direction to move and to locate this copy in relation to said plate, a shaft journaled on the other end of said plate and normally free to rotate in either direction, means for periodically rotating said shaft through a certain part of one revolution, means for adjusting the travel of said periodically rotating means to suit different spacing between the lines of the copy, and means operatively connecting said roller means and said shaft to transmit the rotative movement of said shaft to said roller means to move and index the copy.

17. An apparatus of the character described comprising, a copy support plate, roller means on one end of said plate for suspending and moving the copy, a pair of sight bars in front of said roller means and spaced apart to form a sight space, at least one of said sight bars adjustable to vary the width of said sight space, means for adjusting said roller means to adjust the copy

in relation to said sight space, means on the other end of said plate for indexing the copy in correspondence with the lines thereon, and means operatively connecting said roller means and said indexing means for transmitting the motion of either one of these means to the other.

18. An apparatus of the character described comprising, a copy support plate, roller means on one end of said plate for supporting and moving the copy, a pair of sight bars in front of said roller means and spaced apart to form a sight space, at least one of said sight bars adjustable to vary the width of said sight space, means for adjusting said roller means to adjust the copy in relation to said sight space, means on the other end of said plate for indexing the copy in correspondence with the lines thereon, means for adjusting said index means to differently spaced lines on the copy, and means operatively connecting said roller means and said indexing means for transmitting the motion of either one of these means to the other.

19. An apparatus of the character described comprising means for supporting a copy, a manually operable roller journaled in said means for suspending and selectively moving the copy, means for indexing said copy, and means operatively connecting said indexing means with said roller and disposed intermediate the ends of said means for supporting the copy and on the back thereof.

20. An apparatus of the character described comprising, means for supporting a copy, means for selectively moving said copy, means for indexably moving said copy, means for moving both of said moving means in unison and in either direction when either one of them is operated, and the operating mechanism of said indexably moving means is not affected by said unison moving means.

PETER GRABLER.
